DIE-CASTING MACHINE

Edgar A. Butner, Brooklyn, N. Y., assignor to
Hydropress, Incorporated, New York, N. Y., a
corporation of Delaware

Application September 4, 1946, Serial No. 694,768

5 Claims. (Cl. 22—68)

1

This invention relates to die casting machines or the like and particularly to an automatic feeding device and machine control.

In die casting machines, molten metal is fed to a pressure cylinder, said cylinder communicating with the interior of a die and after metal has been placed in the pressure cylinder, a ram is engaged in said cylinder to force the molten metal into the die. Following filling of the die, excess metal will be present in the pressure cylinder and must be removed and thereafter the die is opened and the cast article taken out.

One of the objects of the invention is to provide a device for automatically feeding molten metal from a reservoir to a cold casting chamber in a more efficient manner than previous devices and to remove the excess solidified metal after an object has been cast so that the cycle of the machine can be repeated.

Another object of the invention is to provide a control for the die casting cycle which can be operated with ease and will be automatic in functioning during various portions of the operation.

One of the features of the present apparatus is a ladle and cooperating pouring trough or guide, said trough moving to a pouring position over the pressure cylinder as the ladle moves from the molten metal reservoir to a metal pouring position. A valve in the ladle is operated to release metal therein when the ladle contacts the trough when the trough is in its metal pouring position. An excess metal slug removing device is moved to a latched or cocked operating position by the trough and is thereafter released at an appropriate time to remove an excess metal slug, the solidified slug having been moved to a position in front of the removing device by a cutoff piston in the pressure cylinder. The cutoff piston first has the function of cutting off the nozzle or passage between the pressure cylinder and the die chamber and thereafter moving a solidified slug of excess metal upwardly to a position to be acted upon by the slug remover.

The control circuit can be arranged so that a single push button or controller may be used to initiate operation of the various portions of the cycle. At the first depression of the switch, the machine automatically operates to close the dies, feed molten metal to the pressure cylinder, and cock the slug remover. At a second operation of the push button, the pressure ram is given a pressure casting stroke and the cutoff piston is operated to close off the nozzle leading to the die chamber. The excess metal is raised after a pre-

2

determined time to a position in front of the slug remover and at this time, the slug remover is tripped so as to remove the excess metal slug from the path of the ram. The dies then are opened so that the casting can be removed and the machine is in readiness for the next casting operation. It is understood, of course, that various materials can be cast or operated upon in suitable machines although the present invention is especially adapted for the cold chamber casting of relatively low melting alloys such as zinc and the like.

These and other objects, features, and advantages of the invention will become apparent from the following description and drawings which are merely exemplary.

In the drawings:

Fig. 1 is a diagrammatic view, partially in section, of one form of the machine.

Fig. 2 is an enlarged plan view taken along the line 2—2 of Fig. 1.

Fig. 3 is a fragmentary enlarged view of the ladle and trough in pouring position.

Fig. 4 is a schematic view of one form of wiring diagram that may be used in conjunction with the operation of the device.

In a preferred embodiment, the machine comprises a crucible 11 for molten material which may be heated in any conventional manner.

Ladle 12 is suspended by means of rods or elements 13 from a slidable sleeve 49 carried by pivoted pin 14, said pin being pivotally supported at 15 to rotatable arms 16. Arms 16 are mounted on shaft 17, said shaft having a pinion 18 attached thereto, said pinion 18 being operable by rack 19, the rack in turn being reciprocable by a motor such as the hydraulic cylinder arrangement 20. Mounted at the ends of the shaft 17 are pinions 21, said pinions being engageable with racks 22, the racks being mounted on cross arm 23. Cross arm 23 is slidably mounted on guide rods 24, said guide rods being fastened to frame 28. Material pouring trough 26 also is mounted on the cross arm 23, said trough having a ladle contacting ring 27. Ladle 12 preferably is bottom pouring and has a valve 47 cooperating with an aperture 48 in the bottom thereof, said valve being fastened to pin 14.

When arms 16 are rotated counterclockwise (Fig. 1) to the position shown in Fig. 3, trough 26 will be moved from a retracted position to a feeding position over pressure cylinder 28. Ladle bowl 12 will come to rest on ring 27 of the trough top and additional movement of arms 16 after the ladle has come to rest will cause pin 14 to

move downwardly relative to sleeve 49 and thus open valve 47 to allow molten metal 50 to flow into trough 26 for feeding to pressure cylinder 28.

Vertical pressure cylinder 28 is mounted on the main frame 28' of the machine for receiving metal from the trough, said cylinder having a nozzle 29 leading therefrom to conduct metal from the pressure cylinder to die 30. Cutoff piston 31 is slideable within pressure cylinder 28, said piston normally being positioned to cutoff the contents of pressure cylinder 28 from nozzle 29, spring 32 normally maintaining piston 31 in the upper position shown in Fig. 1. The other half of the die is seen at 33 and is carried by movable plate 34, said plate being reciprocable by piston 35 of hydraulic cylinder 36. Main ram 37 is enterable into pressure cylinder 28 for forcing metal therein into the closed dies and is operated by hydraulic piston 38.

Tracing the operation of the pressure cylinder and die arrangement during a casting operation, metal is poured into cylinder 28 from trough 26 and then piston 37 descends so as to force metal in cylinder 28 downwardly along with piston 31 until nozzle 29 is uncovered. At this time, the metal will be forced into the dies so as to enter the die chamber formed by closed dies 30 and 33, spring 32 yielding during this operation so as to allow piston 31 to move downwardly. After the casting operation is complete, piston 37 will be raised upwardly, piston 31 being moved back to the position shown in Fig. 1 by spring 32, which will serve to cut off the excess metal at nozzle 29. The excess metal in cylinder 28 then is permitted to solidify, and following this, hydraulic cylinder 39 will operate bell crank lever 39' to move the piston 31 upwardly until the solidified excess metal slug is above face 40' of the frame of the machine or above the top of the pressure cylinder 28.

In order to remove the solidified excess metal slug from the path of the piston and pouring mechanism, a slug remover is provided. The slug remover 40 is seen in a cocked position in Fig. 1 where it previously has been moved by the trough as will be explained hereafter so that band 41 thereof is clear of the bore of the pressure cylinder 28. Remover band 41 is fastened to guides 42, said guides being slideable in members 43. Springs 44 normally urge the slug remover band 41 to the right, Fig. 2 showing the remover in its cocked or energized position. The remover is held in cocked position by means of latch or latches 45 which can be moved to inoperative position by solenoids 46. When solenoids 46 are energized, latches 45 will be moved downwardly so that the force of springs 44 will project the slug remover band 41 rapidly to the right thereby carrying a slug from the top of piston 31, then in its elevated position in pressure cylinder 28.

The slug remover 40 can be moved into a cocked position by cams 60 extending downwardly from trough 26 contacting the cross bar 61 so as to compress springs 44 as the trough 26 moves to the left (Figure 1).

The various hydraulic mechanisms may be controlled by four-way hydraulic valves 51, 52, 53, and 54 in a well known manner. These valves have suitable solenoids as will be described for moving a valve in one direction and a return spring for moving the valve in an opposite direction when the solenoid is deenergized.

As one example of a circuit for automatic operation of the cycle of the die casting apparatus,

reference may be made to Fig. 4 of the drawings. The circuit is arranged so that two operations of a single push button or controller may be used to initiate and complete the entire cycle. The cycle initiated upon a first pressing of the push button includes closing of the die, and simultaneously with said closing, causing the transfer of metal from the crucible to the die casting cylinder. The ladle in this case starts to rotate at the same time the trough is moving into pressure cylinder filling position.

When the pouring of the metal into the die casting cylinder has been completed, the push button is operated a second time to initiate the return of the trough and ladle to a position away from the pressure cylinder, and to move the casting ram or pressure applicator downwardly into the pressure cylinder. A timing circuit also is energized at the second operation of the push button which will initiate return of the ram to its first inoperative position from the pressure or casting position after a predetermined time. The cutoff piston is raised after the casting operation to move upwardly a solidified excess metal slug in the vertical pressure cylinder. After the slug has been moved upward to the top of the cylinder, a further circuit is energized to remove the slug therefrom. Another timer circuit, which was energized at the second operation of the push button, will cause opening of the die after a predetermined time and will clear the various circuits in readiness for the next operation of the machine.

Specifically, push button elements 100 and 101 are connected together mechanically so that switch 100 is normally open and switch 101 is normally closed. The main power leads are indicated at 102 and 103 with a main operating switch 104 which can be closed before the machine is to be operated.

For convenience, the various operating coils are numbered and contactors operated thereby are given a similar number and a distinguishing letter so as to indicate contactors operated by a correspondingly numbered coil. The contacts which are shown as being open in the diagram are normally open and those indicated as being closed are normally closed, a coil upon energization changing the position of the contact from that shown in the drawing.

With switch 104 closed, a first operation of push button 100 will complete a circuit therethrough from lead 102 to 103 through switch operating coil 105. Energization of coil 105 will close five normally open contacts, 105a to 105e. Holding contact 105a will complete a holding circuit around push button 100 so that coil 105 will remain energized when push button 100 is released the first time. Die control contact 105e is closed to energize solenoid 106 controlling the four-way valve 51 for initiating closing of the dies.

Contact 105d is closed to energize ladle switch coil 107 through normally open contact 107a to energize solenoid 109 and move valve 52 to admit pressure to cylinder 20 to commence operation of the ladle 12 from crucible 11 and movement of the trough 26 toward the vertical cylinder 28. Movement of trough 26 to the left will engage slug remover 41 and move the same therewith until latch 45 is forced upwardly by spring 55.

Contact 105b is closed so that when the push button is released, 101 will close (having been opened by depression of 100) and thus complete the circuit from 102 through 101, switch 105b,

coil 116 to lead 103. Coil 116 closes switches in preparation for the second operation of the push button and remains closed until 105 is deenergized by timer 112 at the completion of the casting cycle. Energization of coil 116 will close holding switch 108b serving as a holding circuit therefor. Contact 110a is closed so that the circuit including ram operating switch coil 111 is prepared for the next operation of the push button. Contact 110c is opened so as to separate the circuit containing coil 105 from the circuit containing coil 111.

Upon the next operation of push button 100, a circuit will be established through 110a and ram operating switch coil 111. Contact 111a will serve as a holding circuit for coil 111. Contact 111c will cause energization of timer operating switch coil 108, 108c having been closed by coil 105. This will close holding contact 108b and timer circuit contact 108a and will open normally closed contact 108c thus deenergizing ladle switch coil 107. Deenergization of ladle switch coil 107 will deenergize ladle valve solenoid 109 and thus cause operation of ladle valve 52 to start return of the ladle and trough away from the pouring position. The closing of contact 108a will complete a circuit to the cycle completion timer 112 and ram timer 113, said timers being of any suitable variety such as one of the conventional adjustable electronic type if desired.

Ram operating contact 111d will be closed to energize ram valve solenoid 125 so as to cause operation of ram control valve 53 to admit fluid under pressure to move ram 37 downwardly. After a suitable time delay, ram timer 113 will cause coil 114 to be energized so as to open contact 114a thus deenergizing coil 111. This will open contact 111d and deenergize ram valve solenoid 125 so that the ram 37 will be moved upwardly again after the die casting operation. During the downward movement of the ram, cutoff piston 31 is forced downwardly by ram 37 and as ram 37 moves upwardly, the piston also will move upwardly and shear off the metal at the nozzle 29 thus separating the casting from the metal remaining in pressure cylinder 28. Contact 114b will be closed by coil 114 so as to energize cutoff piston elevating timer 115 to effect a suitable time delay sufficient to allow the metal remaining in pressure cylinder 28 to solidify.

Energization of timer coil 116 will close contact 116a so that when the ram 37 reaches its upper position, ram limit switch 117 will be tripped and closed so as to establish a contact through cutoff piston valve solenoid 118 to cause operation of cutoff piston elevating valve 54 to admit fluid under pressure to cutoff elevating piston 39. The purpose of timer 115 is to insure a sufficient time delay to permit the excess metal to solidify so that even though the ram has tripped the limit switch that valve 54 will not be operated until sufficient time has elapsed to allow the excess metal to solidify.

When cutoff piston 31 has brought a slug to the top of the cylinder 28, cutoff piston limit switch 119 will be tripped closing a contact and energizing coil 120. Slug remover latch trip switch 120b will be closed to energize latch trip coil 46 and release the latch. Contact 120a will be closed to start cutoff piston return timer 121 which after a suitable time will energize coil 122. Opening of contact 122a deenergizes cutoff piston solenoid 118 to permit operation of valve 54 so that cutoff piston 31 again will move to the

lower position shown in Fig. 1. When the cutoff piston 31 has dropped, cutoff piston limit switch 119 will have been released so as to deenergize coil 120 thus opening latch contact 120b and deenergizing solenoid 46 preparing the latch for the next operation of the machine. Simultaneous with the cycle completion, the previously mentioned timer 112, which was energized when the push button was operated the second time, operates to energize coil 124 to open switch 124a deenergizing coil 105 which was energized when the push button was closed the first time which opens all the 105 contacts so that all switches are restored to the position shown in Fig. 4 ready for the next die casting operation. Solenoid 106 will be deenergized so that valve 51 will cause the dies to be opened. Thus the cycle of die casting can be controlled by pushing the same switch twice and the cycle will automatically be carried out and upon completion the device will be in a position to have the cycle repeated for the next die casting operation. The push button or controller may be operated manually or mechanically in any well-known manner or separate controllers may be employed. The details of construction shown are illustrative of one form of the invention and variations may be made therefrom without departing from the spirit of the invention as defined in the appended claims.

It is claimed:

1. In an apparatus for transferring metal from a melting pot to the injection cylinder of a cold chamber die casting machine or the like, the combination comprising a bottom pour transfer receptacle bodily movable from said melting pot to a delivery point, said delivery point being remotely located relative to said melting pot, a separate molten metal guide slidably mounted relative to said injection cylinder for receiving metal from said receptacle at said delivery point and conveying said metal to said injection cylinder, and guide and receptacle moving means moving said guide and receptacle in coordinated relationship to and from said delivery point so that said guide is in position to direct metal to said injection cylinder from said transfer receptacle when both are at said delivery point and the guide is clear of the injection cylinder when injection takes place.

2. In an apparatus for transferring metal from a melting pot to the injection cylinder of a cold chamber die casting machine or the like, the combination comprising a transfer receptacle bodily movable from said melting pot to a delivery point, said receptacle receiving molten metal from said melting pot and carrying the same to said delivery point, a normally closed valve in the bottom of said receptacle, a separate molten metal guide slidably mounted relative to said injection cylinder, means moving said guide and receptacle to and from said delivery point so that said guide is in position to direct metal to said injection cylinder from said transfer receptacle when both are at said delivery point, and automatic valve opening means to open said valve after said receptacle reaches said delivery point to deliver molten metal to said guide.

3. In an apparatus for transferring metal from a melting pot to the injection cylinder of a cold chamber die casting machine, said machine having a die member and an injection cylinder connected to said die, a bottom pour ladle bodily movable from said melting pot to a position ad-

7 jacent said injection cylinder for transferring metal from the melting pot to the injection cylinder, a separate trough slidably mounted relative to said injection cylinder for conveying metal from said ladle to said injection cylinder when said ladle is adjacent said injection cylinder, said ladle and trough being movable to and from a position adjacent said injection cylinder for delivery of metal to the injection cylinder when both are located in a delivery position adjacent said injection cylinder, and means applying pressure to said injection cylinder for forcing metal into said die after said ladle and trough have delivered metal to said injection cylinder and have been moved away from said position adjacent said injection cylinder.

4. In an apparatus for transferring metal from a melting pot to the injection cylinder of a cold chamber die casting machine or the like, the combination comprising a transfer receptacle pivotally mounted on an oscillatable arm means, said receptacle being bodily movable from said melting pot to a delivery position, said receptacle receiving molten metal from said melting pot and carrying the same to said delivery position, a normally closed valve in the bottom of said receptacle, a separate molten metal guide slidably mounted relative to said injection cylinder, gear and rack means interconnecting said guide and said arm means to move the same to and from said delivery position so that said guide is in position to direct metal to said injection cylinder from said transfer receptacle when both are at said delivery point, and automatic valve opening means to open said valve after said receptacle reaches said delivery position to deliver molten metal to said guide.

5. In an apparatus for transferring metal from a melting pot to the injection cylinder of a cold

chamber die casting machine or the like, said machine having a die member and an injection cylinder connected to said die, the combination comprising a ladle bodily movable from said melting pot to a delivery position adjacent said injection cylinder, said ladle having a valve mechanism therein adjacent the bottom thereof and movable relative thereto, a ladle moving mechanism connected with said ladle and valve, 5 a separate trough conveying metal from said ladle to said injection cylinder, operating means moving said ladle moving mechanism, ladle, and trough to and from a cylinder delivery position, means to arrest movement of said ladle in a delivery position, and means moving said ladle moving mechanism beyond said delivery position of the ladle, so as to move said valve mechanism relative to said ladle to deliver metal from said ladle to said trough from which it is delivered to said cylinder.
